UNITED STATES PATENT OFFICE.

JOHN T. RIDDELL, OF EVANSTON, ILLINOIS.

APPARATUS FOR MAKING INFLATABLE BALL COVERS.

Application filed April 10, 1926. Serial No. 101,217.

My invention relates to improvements in apparatus for making inflatable ball covers and has for its object the provision of improved means for making covers for footballs, 5 basketballs and the like whereby such balls of uniform shape may be provided.

Other objects will appear hereinafter.

The invention consists in the combination and arrangements of parts hereinafter described and claimed.

The invention will be best understood by reference to the accompanying drawings forming a part of this specification, and in which,

15 Fig. 1 is a longitudinal section of apparatus embodying the invention;

Fig. 2 a section taken substantially on line 2—2 of Fig. 1;

20 Fig. 3 a section taken substantially on line 3—3 of Fig. 1, the form being illustrated as collapsed; and

Fig. 4 a view of a ball cover completed and ready for reversing.

The preferred form of apparatus for carrying out the invention consists of a collapsible form of an exterior or peripheral shape conforming to the desired interior of the completed ball. The form illustrated consists of a central openwork frame 5 having peripheral portions 6 constituting portions of the periphery of the form and having such desired shape. Retractable end members 7 are slidably mounted in the body or frame thus provided, said end members carrying guide ribs 8 operating in guide grooves 9 in the frame whereby said end members will be guided in their movements. Threaded shafts 10 are mounted as shown in the central frame work 5 of the form and engage suitable threaded sockets in the end members 7 whereby by a rotation of said shafts in opposite directions the end members 7 will be simultaneously retracted or protruded. The shafts 10 carry bevel gears 11 meshing with bevel gear 12 on a transverse shaft 13. The transverse shaft 13 is also suitably mounted in the central framework of the form and is provided with oppositely threaded portions 14 and 15. Opposite side members 16 are provided in said form as shown and constitute the periphery of a large portion of the sides of the form. These side members 16 are also provided with guide ribs 17 engaging guide grooves 18 in the frame the form for guiding the movements 55 of said side members. Each of the side mem-

bers 16 is provided with threaded engagement as shown with the threaded portions of the shaft 13 and shaft 13 is provided with a squared end 19 by means of which the same may be rotated as desired. The squared end 19 60 is provided with a transverse opening 20 for the reception of a rod or wire for suspending or mounting the form and also for operating the shafts if desired.

I have illustrated apparatus adapted for 65 the manufacture of an ordinary football cover. In carrying on such manufacture the football cover is provided as usual in the form of four similar leather parts 21 which when properly assembled will constitute the cover 70 of an ordinary oval-shaped football. These cover parts are suitably dampened and are then stretched and sewed together over said form, French seams 22 being employed for such purpose as indicated. On the side of 75 the form where the shaft end 19 protrudes, the seam is not completed, two end portions 23 being formed leaving the usual gap or opening 24 for the insertion of the usual rubber inflating ball, lacing openings 25 being provided on opposite sides of said opening for lacing the ball in the usual way. After this sewing has been completed, if desired, the French seams may be flattened by pounding or rolling them against the inner form. 80 Then the seam portions 23 are ripped out to permit of removal of the cover thus formed from the form and the form is collapsed as much as possible by rotating shaft 13 whereupon said cover may be removed from the 85 form. Then the seam portions 23 are remade, preferably using the same stitch holes which were left by ripping out the original seam portions 23. In this way, it is insured that the cover will be reformed in exact conformity with the shape assumed originally over the form. If the same stitch holes are not employed for the resewing, care should be taken that the same is resewed substantially 90 along the same lines of stitching so as to insure uniformity in the product. Then the cover thus formed is reversed through the slit opening 24 and is ready for use in the usual way. In this way balls of absolutely 95 uniform shape and contour may be provided, thus greatly adding to the accuracy with which the same may be used. Where balls of different shapes and for different purposes are to be made, the form will of course conform to the desired interior thereof and the 100 105 110

cover portions will also be varied in shape to correspond or facilitate the manufacture as desired.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

The art or method of forming ball covers as herein disclosed, is not claimed in this application, because it is made the subject matter of claims in my copending divisional application Serial No. 157,665, filed December 29, 1926.

Having described my invention, what I claim as new and desire to secure by Letters Patent is:

1. A form member in the shape of the interior of a ball cover comprising a central frame having a portion thereof constituting a portion of the periphery of said form;

guideways in said frame; end members movable in said guideways; and means for retracting and protruding said end members, substantially as described.

2. A collapsible form member in the shape of the interior of an inflatable ball cover comprising retractable and protrudable end members; retractable and protrudable opposite side members; and means for simultaneously retracting and protruding said end members and side members, substantially as described.

3. A collapsible form member in the shape of the interior of an inflatable ball cover comprising retractable and protrudable end members; retractable and protrudable opposite side members; a plurality of threaded shafts operatively engaging said retractable and protrudable end members and side members; gearing connecting said shafts for simultaneous operation thereof for simultaneously retracting and protruding said end members and side members; and means for rotating one of said shafts, substantially as described.

In testimony whereof I have signed my name to this specification.

JOHN T. RIDDELL.
